HARRY U. BADEAU, OF BRIDGEPORT, CONNECTICUT, ASSIGNOR TO THE PERKINS ELECTRIC SWITCH MANUFACTURING COMPANY, OF BRIDGEPORT, CONNECTICUT, A CORPORATION OF CONNECTICUT.

PANEL-BOARD FITTING.

1,141,032.

Specification of Letters Patent. Patented May 25, 1915.

Application filed September 15, 1914. Serial No. 861,797.

To all whom it may concern:

Be it known that I, HARRY U. BADEAU, a citizen of the United States of America, and residing at Bridgeport, in the county 5 of Fairfield and State of Connecticut, have invented a certain new and Improved Panel-Board Fitting, of which the following is a specification.

My invention relates to panel board fittings and particularly to an improved cover 10 for switch fittings, the object of my device being to provide a cover which may be used on the fitting irrespective of the manner in which the latter must be arranged to accommodate it to the direction in which the 15 branch wires are led from the mains.

In the accompanying drawings, Figure 1 is a plan partially broken away showing a switch fitting to which a cover embodying 20 my invention in one form is applied; Fig. 2 is a plan of the same with the branch wires extending in the opposite direction; Fig. 3 is an end elevation of the fitting; and Fig. 4 is a cross section on the line 4—4, Fig. 1.

The fitting here shown is of common type comprising an insulating base 5 having adjacent one end transverse grooves 6, for the cable mains 7. Connections are made in the usual manner therefrom to the branch wires 30 8, through the switch S and fuse plugs (not shown) inserted in the receptacles 9. It has already been proposed to cover a fitting of this character with an insulated metallic cover plate; but as heretofore constructed it 35 is necessary to carry a double line of cover plates, one style for fittings so arranged that the branch wires are led in one direction from the mains, and a second style for fittings so arranged that the branch wires extend in the opposite direction from the mains, or in other words, where the base of 40 the fitting is mounted in reversed position.

The present cover plate may be used whether the fitting is so arranged that the branch wires extend from one side or the other of the mains. In the form here shown the cover comprises a sheet metal plate 10 substantially co-extensive in area with the base 5 and insulated therefrom and from 50 the metal parts mounted thereon, by a sheet of fiber, heavy paper or other insulating lining 11, attached thereto by rivets 12. The cover plate is apertured in register with the fuse plug receptacles 9 and it is also pro-

vided with a boss 13, centrally apertured at 55 14 to permit the switch stem 15 to extend above the plate and receive the operating thumb piece 16. On the switch spindle is carried an indicating dial 17 which rotates with the switch mechanism and carries suitable indications to disclose the "on" or "off" position of the switch S. The insulating lining 11 is segmentally apertured at 18^a, 18^b on opposite sides of the switch spindle in register with the indications on 60 the dial 17 and thus affords sight apertures through which the indications may be read.

The cover plate 10 is provided with elongated apertures 19^a, 19^b, overlying the sight apertures 18^a, 18^b in the lining 11 and 70 formed in pressed-up channels 20^a, 20^b, which extend longitudinally inward from one end of the cover plate. Each channel affords a guideway for a strip 21 of paper, celluloid, or the like carrying a legend to 75 indicate the circuit controlled by the switch S. This legend is written at one end of the strip 21 so that when the latter is inserted between the insulating lining 11, and the face plate 10, in the channel 20^b, the legend 80 is exposed at the aperture 19^b. Inasmuch as the strip 21 overlies the lining 11, it covers the sight aperture 18^b, therein and the dial 17 is visible only through the apertures 18^a and 19^a. 85

When the position of the fitting is reversed from that shown in Fig. 1, so that the branch wires 8 lead to the right, (as in Fig. 2), the legend strip 21 is removed from channel 20^b, turned over to expose the 90 printed legend on its opposite face, and inserted in channel 20^a which is now lowermost, and through which the printed "on" or "off" on the dial 17 (thereby obscured) would read backward. The dial 17 is now 95 exposed through apertures 18^b and 19^b. Where a number of fittings are arranged on a panel leading the branch wires from opposite sides of central mains, the dial sight apertures are thus maintained uniformly 100 above the switch buttons 16, while the circuit legends are arranged uniformly below the buttons, thus presenting a desirable appearance of symmetry.

The cover plate is secured to the fitting 105 by means of the switch thumb piece 16, and also by the heads of fuse plugs when the latter are inserted in the receptacles 9. To

further position the cover upon the fitting, it is provided with a teat 22 which enters a recess 23 in the upper face of the base of the porcelain. The plate is thus prevented 5 from swiveling on the switch spindle 15 when there are no fuse plugs inserted in the receptacles 9.

Various modifications of the construction shown will readily suggest themselves, and 10 I do not limit my invention to the particular features shown.

I claim as my invention:

1. In panel board fittings, a sheet metal cover plate apertured to permit the passage of 15 a switch stem therethrough and having apertures spaced therefrom and symmetrically arranged on opposite sides thereof, a switch indicating dial having a lettered portion in register with said apertures, a circuit legend 20 carrier adjustable at either of said apertures and serving to obscure the dial at one aperture, together with means for holding said legend carrier in adjusted position.

2. In panel board fittings, a sheet metal 25 cover plate having a raised boss centrally apertured to permit the passage of a switch spindle therethrough and apertures in said cover plate symmetrically arranged on opposite sides of said boss, a switch indicating 30 dial having a lettered portion in register with said apertures and a circuit legend carrier adjustable at either of said apertures and serving to obscure the dial at one aperture, together with means for holding said 35 legend carrier in adjusted position.

3. In panel board fittings, a sheet metal cover apertured to permit the passage of a switch stem therethrough, longitudinal channels in said cover plate extending from 40 one end thereof past said aperture for the switch spindle and symmetrically arranged on opposite sides thereof, said channels being apertured, a switch indicating dial having a lettered portion in register with said apertures and a circuit legend carrier adjustable 45 at either of said apertures and serving to obscure the dial at one aperture, together with means for holding said legend carrier in adjusted position.

50 4. In panel board fittings, a sheet metal cover plate having a raised boss centrally apertured to permit the passage of a switch spindle therethrough, longitudinal channels formed in said cover plate symmetrically on

opposite sides of said boss and extending 55 to one end of said cover plate, said channels being apertured symmetrically on opposite sides of the boss, together with a switch dial having a lettered portion in register with said apertures, and a circuit 60 legend carrier fitting in either of said channels and serving to obscure the switch dial at one aperture, substantially as described.

5. In panel board fittings, a sheet metal cover plate having a raised boss centrally 65 apertured to permit the passage of a switch spindle therethrough, and channels formed in said cover plate on opposite sides of said boss and apertured symmetrically with relation thereto, an insulating lining for 70 said cover plate apertured symmetrically on opposite sides of said boss and within the area of the apertures in said channels, together with a circuit legend carrier adjustable in either of said channels between the 75 lining and the cover plate and serving to obscure one of the apertures in the lining.

6. In panel board fittings, a sheet metal cover plate having a raised boss centrally 80 apertured to permit the passage of a switch spindle therethrough, channels formed in said cover plate symmetrically on opposite sides of said boss and extending to one end of the cover plate, said channels having elongated apertures formed therein symmetrically 85 on opposite sides of said boss, an insulating lining for said plate segmentally apertured symmetrically on opposite sides of said boss within the area of the elongated apertures of the channels, together with a 90 switch dial visible through said apertures and a circuit legend carrier adjustable in either of said channels and obscuring the dial at one of said apertures, substantially 95 as described.

7. In panel board fittings, a sheet metal cover plate apertured to permit the passage of a switch stem therethrough, a teat at the opposite end of said cover plate, said fitting having a base apertured to receive said teat, 100 for the purpose described.

In testimony whereof I have signed my name to this specification, in the presence of two subscribing witnesses.

H. U. BADEAU.
